UNITED STATES PATENT OFFICE.

DORR R. MARTIN, OF DETROIT, MICHIGAN.

THERMOSTATIC CONTROL DEVICE FOR FUEL BURNERS.

Application filed February 3, 1922. Serial No. 533,855.

To all whom it may concern:

Be it known that I, DORR R. MARTIN, a citizen of the United States, residing at Detroit, county of Wayne, State of Michigan, have invented a certain new and useful Improvement in Thermostatic Control Devices for Fuel Burners, and declare the following to be a full, clear, and exact description of the same, such as will enable others skilled in the art to which it pertains to make and use the same, reference being had to the accompanying drawings, which form a part of this specification.

This invention relates to control devices for fuel burners, and the principal object of the invention is to provide means in conjunction with a thermostat for varying the intensity of the flame of the burner of heating plants whereby a room temperature may be maintained between certain high and low limits of temperature, the thermostat being utilized to increase or decrease the flame of the burner corresponding to inverse variations in the room temperature influenced by the burner. Various heating appliances having burners have been used utilizing kerosene, fuel oil or gas as the heating element. In such former devices the oil or gas is discharged under pressure to the burner and sometimes air or steam pressure is used with the oil to produce the desired character of flame. In either of such former devices the pressure or volume of the oil flow may be varied or the pressure or volume of air and oil or steam and oil may be varied or the volume of flow of gas may be varied to vary the intensity of the flame of the burner, and it is to be understood that this invention may be used with any of such burners, and that the control valve may be placed as is found necessary or desirable to control the fuel flow in a manner to vary the flame intensity. With a house heating system for instance, the burner is usually employed with a steam heating device and as the room temperature increases, my control device tends to decrease the intensity of the flame and, as the room temperature falls, the apparatus operates to increase the flame intensity, and it is to be understood that various devices may be utilized in conjunction with a thermostat and control valve of the burner to vary the flame. Another object of this invention is to provide an electrical device controlled by a thermostat and

adapted to vary the intensity of the heat of the burner inversely to variation in the room temperature. An additional object of the invention is to provide an electrical device for controlling the valve of the fuel supply line to vary the volume of flow of fuel supply to the burner to vary the intensity of the heat thereof. Further objects of the invention are involved in the structural features and arrangements of parts as hereinafter more fully described and claimed, and the preferred form of construction of a device embodying my invention is indicated in the accompanying drawing which is a view partly diagrammatic in form showing my improved control apparatus and thermostat and indicating a burner and supply line therefor.

The burner may be of any approved type of oil or gas burner, one type of which is indicated at 1 having a supply line or conduit 2 for a fluid fuel. The burner has a discharge nozzle and out of the forward end 3 of the burner, flame is projected as indicated by dotted lines. It is to be understood that the burner is applied to a heating appliance (as for instance a steam furnace not here shown), but by means of which a room or building is to be heated. In the supply line 2 is provided a valve 4 having an operating lever 5 therefor which may be turned to decrease or increase the volume of flow of fuel. It is to be noted that I have here shown the conduit 2 as being a fuel line. Many burners are provided with a fuel line and an additional air or steam line, and the valve for controlling the intensity of the flame may be in the air or steam line by variation of the volume of which the amount of actual fuel or intensity of the flame of the burner may be varied. With the conduit 2 here shown, oil under pressure is to be considered as being discharged to a burner therethrough and the valve 4, through manipulation of the lever 5, is utilized to vary the volume of flow of fuel from nothing to the fuel capacity of the line 2.

The thermostat is indicated diagrammatically at 6 and should be of a character to move the contact point a considerable extent for each degree or part of a degree of change in temperature, and I have devised a successful structure for this purpose which consists of a strip of iron and a strip of hard rubber secured together,

Hard rubber has a very high coefficient of expansion while the metal strip has comparatively low coefficient of expansion so that a slight change of temperature causes 5 a considerable movement of the contact element. Other structures may be used if desired to secure the desired range of movement of contact point. By such arrangement the contacts 8, 9, 10 and 11 may be 10 placed a considerable distance apart. With a strip of hard rubber and soft iron as mentioned, twelve inches in length, the spacing of the contact points 8 to 11 inclusive may be about three-eighths of an inch center to center and with such spacing there is no possibility of more than one contact point being included in circuit at the same interval.

Various devices may be utilized between the thermostat and the lever 5 of the valve 20 4 which is to be actuated. Preferably I employ an electrical device controlled by electric circuits established through movement of the thermostat across the contact points. The device consists of a casing 12 in which 25 is mounted a shaft 13 carried in bearings or supported in the case and adapted for longitudinal movement therein. The forward end of the shaft is connected by means of a link 14 with the end of the lever 5 and 30 longitudinal movement of the shaft, caused as hereinafter stated, actuates the lever 5 to control the valve between full open or closed position, such movement of the lever 5 being indicated by dotted lines 35 in the drawing. At the forward end of the casing 12 are positioned four coils, 15, 16, 17 and 18 providing solenoids with central apertures thereof in alignment. The solenoids lie end to end and a core 19 40 is provided on the shaft 13. The core 19 is of soft iron and the shaft 13 should be of brass or non-magnetic material. The shaft is also provided with a series of notches 20, 21, 22 and 23 corresponding 45 to the number of solenoid coils and in these notches is normally projected a latch 24 projected downwardly into the notch by a spring 25 in a solenoid case 26 on the upper side of the casing 12. This shaft 24 50 carries a core 27 which is common to four solenoids 28, 29, 30 and 31 that are in concentric relation, the core being movable on the axis of the several coils. There is a circuit for each of the solenoids 15, 16, 17 55 and 18 which consists respectively of the lines 32, 33, 34 and 35 running respectively to the contacts 11, 10, 9 and 8 heretofore mentioned. The source of energy is indicated as a battery 36 connected directly to 60 the thermostatic element in the structure here shown by a line 37 and the return line of the solenoids 15, 16, 17 and 18 is indicated at 38, 39, 40 and 41 connecting by a common line 42 with the opposite side of 65 the battery. It is first to be noted that con-

tact of the point 7 of the member 6 with the contact 9 of the line 34 will energize the coil 17 and draw the core 19 to the position shown in the drawing in which position the valve 4 is partly open and under which condition a certain intensity of flame is produced determined by the volume of fuel permitted to pass the valve 4. If the flame and the heat developed in the room by the heating appliance to which the burner is applied is not sufficient to prevent a drop of temperature in the room, the thermostat will continue to move toward the right and engage the contact 10 for the line 33 which will energize the coil to draw 70 the core 19 and shaft 13 to the right of the position shown in the drawing increasing the opening of the valve and correspondingly increasing the intensity and heat of the burner. Each of the circuits 32, 33, 34 and 35 have a make and break switch 43 located within the casing 12 and this may conveniently consist of a contact 44 which is held in fixed position by a stud 45 and on this stud normally insulated from the contact bar 44 is a spring contact bar 46 having a lug 47 which normally rides on the surface of the shaft holding the contact points between the members 44 and 47 closed. Each line 32, 33, 34 or 35 is connected to 80 the member 46 of its respective switch and continues with the member 44 of the respective switch. Thus when these contact points 47 ride on the surface of the shaft, as is shown with the switches of the lines 32, 33 and 35, the circuit from the contact points 8, 10 and 11 to the solenoids is unbroken. Therefore if the thermostat contact 7 moves to engage the contact 8, the circuit is established through the solenoid 18 85 which should draw the core 19 to the left of the position shown as will be readily understood. In order that there may not be an excessive current consumption I have provided a notch 48 in the shaft 13 which, for instance on the closing of the circuit through the contact 8 and solenoid 18, would be drawn to the left of the position shown through movement of the solenoid member 19 and the point 47 of the switch 43 in the line 35 (due to the fact that the member 46 is in the nature of a spring) 90 would drop into the notch and break the circuit after it was established by the thermostat. In such movement of the shaft 13 the switch device in the line 34 would then be closed and thus each of the make and break switches 43 of the several lines upon the closing of the respective circuit by 95 movement of the thermostat operate to break the established circuit as the notch 48 is brought to registration with the respective switch device by movement of the shaft 13. 100

The solenoids 28, 29, 30 and 31 are small 105

- in comparison to the solenoids 15 to 18 and are connected in parallel therewith. The solenoid 31 has a line 49 connected with the line 32, the solenoid 30 has a line 50 connected with the line 33, the solenoid 29 has a line 51 connected with the line 34, and the solenoid 28 has a line 52 connected with the line 35. Each of these solenoids has a return line 53 connected with the main return line 42. Normally the solenoid 27 is projected downward by the spring 25 holding the end of the latch or shaft 24 in a notch of the shaft 13 and thus prevents accidental displacement of the shaft 13 and consequently holds the valve 4 in the set position. Upon energization of any one of the circuits 32, 33, 34 and 35 the solenoid core 27 is raised releasing the shaft to movement by the practically simultaneously energized solenoid 15, 16, 17 or 18 as the case may be. Energization of either of these last named solenoids moves the shaft 13 to certain position due to centralization of the core 19 with the energized solenoid and which positions one of the notches 20, 21, 22 or 23 in alignment with the latch or shaft 24 of the core 27 and upon breaking of the circuit through the opening of the respective switch member 43, as heretofore stated, the core 27 is projected downward by the spring 25 locating the shaft 13 in position. The contact points 8 to 11 for the thermostat may be spaced a sufficient distance to require any desired change in temperature as for instance one degree of temperature change to produce the necessary movement of the thermostat to pass from one contact point to another. Considering that the contact points 8 to 11 represent a range of temperature from 69 to 72 degrees and if the temperature of the room in which the thermostat is placed is decreasing when the thermostat is set to energize the line 34 and solenoid 17, the thermostat will act and move to contact with the point 10 energizing the solenoid 16 and thereby open the fuel line to a greater extent to increase the heat of the room through the heating appliance. On the other hand if the temperature of the room is increasing under the condition above stated, then the thermostat would tend to move to engage contact 8 and close the valve 4 and cut off the flame from the burner. It is to be understood that an ordinary oil or gas burner may be used with this control device, the burner illustrated being of the fuel oil type. From the foregoing description it is evident that a room may be maintained within a particular range of temperature by the apparatus herein shown. It is believed to be fundamentally new to use a thermostatic device to vary the intensity of the heat applied to a heating device by which the temperature of the room is to be maintained. Thermostats have been used to manipulate the draft devices of the furnace whereby the rapidity of combustion of fuel as for instance coal may be varied. My invention differs in this respect, that the thermostat is here utilized in combination with various elements which directly and immediately vary the intensity of heat applied to the furnace.
- Having thus fully described my invention, what I claim and desire to secure by Letters Patent of the United States is—
1. The combination with a heating appliance and a fuel burner through which fuel is discharged for combustion, means for controlling the intensity of the heat of combustion comprising apparatus for varying the volume of fuel discharged per unit of time, a control device for operating the same, said control device comprising a rod connected with the volume varying apparatus, electro-magnetic means for moving the rod step by step to increase or decrease the volume of flow of fuel, a series of circuits for the said electro-magnetic means through energization of each of which the rod is moved a certain distance, and a thermostat adapted by temperature change in the area heated by the appliance to successively make or break the circuits, the parts being so arranged that a decrease in temperature of the area heated by the appliance causes the element to successively make the circuits and move the rod to increase the flow of fuel and an increase in temperature causes the thermostat to break the circuits successively and move the rod to decrease the volume of flow of fuel.
  2. The combination with a fluid fuel burner for a heating appliance, of a temperature controlled device for varying the flow of fuel to the burner, said device being actuated through variation in temperature of the heated area and consisting of a valve adapted to be actuated to vary the volume of flow of fuel to the burner, an element movable to operate the valve, a series of solenoids in axial alignment, a core therefor carrying the said movable element, a series of circuits for each solenoid, a contact point for each circuit, a thermostat, a contact member movable by the thermostat from one contact point to the other to successively complete the respective circuits, a decrease in temperature of the area heated causing the thermostat to increase the flow of fuel and an increase in temperature of the heated area causing the thermostat to decrease the flow of fuel.
  3. The combination with a fluid fuel burner for a heating appliance, of a control device influenced through variation of temperature of the area heated by the appliance to vary the volume of flow of fuel to the

burner comprising a valve for the fuel supply, a lever for actuating the valve, a movable element connected therewith, a series of solenoids in axial alignment, a common core therefor for moving said element, a circuit for each of the solenoids, and a contact device adapted to close the circuits in succession in one direction or the other upon increase or decrease respectively of the temperature of the heated area.

4. The combination with a liquid fuel burner and supply line therefor, of a valve in the said line adapted to be turned to vary the volume of flow of fuel through the supply line, a movable element by means of which the valve is actuated to increase or decrease the flow, a series of solenoids in axial alignment, a common core therefor connected with the movable element, a circuit for each of the solenoids each circuit having a contact point, a thermostatic element influenced by increase or decrease in temperature to successively engage the contacts, movement in one direction step by step energizing the solenoids and increasing the opening of the valve and in the reverse direction step by step increasing the closing of the valve, and means for breaking the circuit of the energized solenoid upon movement of the core through the influence thereof.

5. A thermostatically controlled device for varying the flow of fuel to a burner comprising the combination with the burner and supply line thereof, of a valve in the line adapted to be turned from a closed to open position or reversely, an element for actuating the valve, a series of solenoids in axial alignment, a common core therefor actuating

the movable element, a circuit for each of the solenoids including a thermostatic device, a series of contacts one for each of the circuits adapted to be engaged and the circuit completed through movement of the thermostat, a make and break switch in each of the said circuits, energization of a solenoid through closing of its contact causing movement of the solenoid core and corresponding movement of the valve and means whereby the switch of the circuit of the energized solenoid is broken as the core moves to its position.

6. The combination with a fuel burner for a heating appliance, of a control device influenced through variation of the temperature of the area heated by the appliance to vary the volume of flow of fuel to the burner, said control device consisting of a valve for the fuel supply to the burner, a movable element connected therewith, a series of solenoids in axial alignment, a common core for the solenoids adapted to move the element as the core is moved, a circuit for each of the solenoids, a thermostatically controlled device for closing the solenoid circuits in succession as it is moved in one direction or the other by increase or decrease in temperature of the heated area and to move the movable element to inversely vary the supply to the burner, and an electrically controlled device for locking the movable element subsequent to movement by energization of a solenoid.

In testimony whereof, I sign this specification.

DORR R. MARTIN.
